UNITED STATES PATENT OFFICE.

CHARLES F. THATCHER, OF PROVIDENCE, RHODE ISLAND.

JAR-TOP FASTENING.

1,292,920.

Specification of Letters Patent. Patented Jan. 28, 1919.

Application filed May 6, 1918. Serial No. 232,693.

To all whom it may concern:

Be it known that I, CHARLES F. THATCHER, a citizen of the United States, residing at Providence, in the county of Providence and 5 State of Rhode Island, have invented a new and useful Improvement in Jar-Top Fastenings, of which the following is a specification.

This invention relates to certain new and 10 useful improvements in jar top fastenings, and the primary object thereof is to provide a fastening which is capable of holding the top in a position so as to permit the escape of vapors during the heating of the contents, 15 and which is also capable, upon a further movement, of positively locking the top in a position so as to seal the jar.

The invention further has for its object 20 to provide a fastening which is simple and capable of easy and ready operation, and to also enable the production to be effected with minimum expense.

Further and other objects will be later set forth and manifested in the course of the 25 following description.

In the drawings—

Figure 1 is a fragmentary view, in section, showing the invention applied to a jar.

Fig. 2 is a section taken on line 2—2 of 30 Fig. 1.

Fig. 3 is a side elevation.

The jar A is provided with a peripheral sharp or clean cut ledge B, and has the usual gasket seat C on which the gasket D engages, 35 the latter in turn being engaged by the top E. The top has the common form of bail seat F, in which the horizontal part 1 of the bail engages. The bail is formed with depending vertical or right angular side arms 40 2, which latter extend below the ledge B, and are formed with circular eyes or loops 3. As depicted in Fig. 3, the loops are bent so as to provide parts which engage beneath and with the ledge B, so as to ride thereon 45 and in a manner later set forth. The ends of the side arms are extended horizontally at 4, and are curved so as to conform to the jar exterior as depicted in Fig. 2, to form operating arms or parts, the latter at their 50 free ends being formed with loops 5, to form finger engaging members, and also locks, as will be now described.

The fastening is applied so as to occupy the position shown in full lines in Fig. 1, 55 in which position of the parts it will be seen that the loops 3 engage beneath the ledge B,

with the locks 5, however, disposed above the ledge. This disposition of the locks permits the top E to move upwardly to a slight and predetermined extent, so that 60 during the cooking or heating of the contents of the jar, the latter having therein the fruits or vegetables to be preserved, the vapors resulting from such heating will be free to escape. After the heating has been 65 completed, and the contents are in condition so as to seal the jar, then the loops 5 are forced downwardly by the fingers or otherwise, so as to engage beneath the ledge B. This action results in the arms 2 and loops 70 3 being thrown or moved forwardly to the dotted line position of Fig. 1, and since the loops 5 are disposed below the ledge B, it will be apparent that the top is effectively 75 and positively held against any upward movement. In this manner, the top is initially locked to a partial extent, and is subsequently locked so as to seal the jar.

In order to release the top and permit of its removal it is merely necessary to move 80 the loops 5 from the dotted line position of Fig. 1 to the full line position of said figure and to then move the side arms 2 in the direction of the loops 5, so as to entirely 85 disengage the fastening device from the top E.

It will also be apparent that since the arms 2 and the horizontal parts 4 thereof are independent of one another, less force 90 will be necessary to operate the arms, rendering it easier for the operator to manipulate the parts.

Having thus described my invention, I 95 claim as new and desire to secure by Letters Patent:—

1. In combination with a jar having a circular ledge below its top, a fastening composed of a bail having a horizontal member extending across the top and having depending vertical side arms, said arms having circular loops engageable with said ledge and having horizontal parts extending outwardly from the loops and formed with loops at their free ends for engagement with the ledge to lock the top in place, 100 said last named loops being independently movable to extend above the ledge so as to hold the top in place to permit the escape of vapors, and upon down movement to engage beneath and with the ledge acting to 105 move the depending arms forwardly to lock the top in sealed position.

2. In combination with a jar having a ledge below the top thereof, a fastener for the top composed of a member engaging on the top and having depending side arms provided with loops engageable beneath said ledge, and independently movable parts disposed at right angles to the arms and formed to engage beneath said ledge to lock the fastener in position with the top sealed.
- 10 3. In combination with a jar having a ledge below its top, a fastener formed from one piece of material comprising a bail member having vertical side arms, said arms having independently movable loops engageable with said ledge and outwardly extending parts formed to engage with the ledge to lock the top in place.

In testimony whereof I have signed my name to this specification in the presence of two subscribing witnesses.

CHARLES F. THATCHER.

Witnesses:

ADA E. HAGERTY,
J. A. MILLER.
